UNITED STATES PATENT OFFICE.

GERTRUDE CRUMLEY, OF CHEROKEE, OKLAHOMA.

STOVE ATTACHMENT.

1,151,569.

Specification of Letters Patent. Patented Aug. 31, 1915.

Application filed October 9, 1913. Serial No. 794,247.

To all whom it may concern:

Be it known that I, GERTRUDE CRUMLEY, citizen of the United States, residing at Cherokee, in the county of Alfalfa and State 5 of Oklahoma, have invented certain new and useful Improvements in Stove Attachments, of which the following is a specification.

This invention relates to an improved attachment for gas and oil stoves.

10 The primary object of the invention contemplates the provision of a specially constructed plate attachment having a plurality of either staggered or uniformly spaced apart openings formed therein, the said 15 openings providing a means whereby the heat generated in the usual manner may be uniformly directed upon the bottom of the kettle, flat-iron, pan or other article to be heated, thereby avoiding the loss or heat 20 waste now occurring where solid stove lids are employed in connection with gas and oil stoves to enable and facilitate the cooking or heating of foods or articles wherein a slow steady uniform heat is desired.

25 A further object of the invention resides in the provision of a plurality of uniformly spaced support members, either formed integrally with or secured to the under side of the plate to serve not only as a support 30 therefor, but to also serve in the capacity of guides, which when arranged over the usual open jet will direct the heat through the plate openings for the purpose above specified.

35 A still further object of this invention is to construct the attachment with such regard to proportion, arrangement and number of parts that it may be cheaply manufactured, and may be readily and conveniently applied or employed in connection 40 with any stove of standard type.

The above and additional objects are accomplished by such means as are illustrated in their preferred embodiment in the accompanying drawings, described in the following specification and then more particularly pointed out in the claims which are appended hereto and form a part of this application.

50 In describing my invention in detail reference will be had to the accompanying drawings wherein like characters denote like or corresponding parts throughout the several views, and in which:—

55 Figure 1 is a top plan view of an attachment constructed in accordance with my in-

vention; Fig. 2 is an inverted plan view; and Fig. 3 is a side elevation of the device.

Before proceeding with the description of the drawings, I desire to call particular attention to the fact that while I have evolved my invention with particular reference to its application in connection with gas and oil stoves, the same may be readily utilized in connection with ranges of various types as a 60 substitute for the usual solid lids now associated therewith.

Referring now to the drawings wherein is illustrated the preferred embodiment of my invention the numeral 1 designates the plate 70 as an entirety, the same being preferably oval in outline and provided at one end with a plurality of uniformly spaced openings or slots 2 arranged preferably in series of circles, the said series radiating from a point 75 forming the center around which the several series of arcuate openings are described.

Upon the under face of the plate member 1, the latter being preferably of thin cast iron, I provide a plurality of support members, the said members radiating from the inner circle of openings 2 to a point slightly beyond the outer circle of openings, to not only reinforce the plate member at its weakest point, but to also serve in the capacity of guides, one being disposed between each series of openings, to direct and cause the heat generated therebeneath to be uniformly fed to the said openings 2 where it is uniformly and subsequently directed against 90 the bottom of the article to be heated, the said article to be positioned, during the application of the invention upon the outer or upper face directly over the said openings.

When it is desired that the article to be 95 heated should receive its heat in a slow, steady and uniform manner, the same is placed upon the imperforate portion of the plate member 1 formed at one side of the openings 2 therein, which arrangement of 100 the article thereupon, will, to a certain extent retain the heat and permit the food to be slowly cooked or the article to be slowly heated.

Upon the under side of the imperforate portion of the plate member 1, I provide a plurality of uniformly spaced support members 4, the same radiating from a point in spaced relation to the extremity of one of the support members above mentioned. In 110 application, the plate member 1 is positioned over the usual open jet of the ordinary gas

or oil stove now universally used throughout the suburban districts. When thus positioned, the heat generated therebeneath is directed to and through the openings 2 at the perforate end of the plate member 1 by means of the guides 3 provided therefor, thereby heating the article placed over the said openings in a steady uniform and efficient manner. The article after having 10 been heated to the desired degree may be removed from over the openings 2 and placed at one side of and upon the imperforate portion of the plate member 1 where it is maintained at an even temperature for the length 15 of time required.

From the above, taken in connection with the accompanying drawings it is apparent that articles of small size may be heated, either the imperforate or perforate portion 20 of the plate member 1 serving as a support therefor; that the device may be used as a stove lid to facilitate the heating of articles placed thereupon; and that fuel, to a material extent, is saved by the application of the 25 present invention.

It will be understood that the above description and accompanying drawings comprehend only the general and preferred embodiment of my invention and that various 30 minor changes in details of construction, proportion and arrangement of parts may

be made within the scope of the device as claimed and without sacrificing any of the advantages of my invention.

Having thus fully described my invention, 35 what I claim as new and desire to secure by Letters Patent, is:—

1. A stove attachment, including a plate member having a plurality of concentric series of elongated openings, said series of 40 openings increasing in size away from the point of radiation, and flanges disposed between the openings to direct heat thereinto.

2. A stove attachment including a plate 45 member provided with elongated openings adjacent one end thereof, said openings being substantially arcuate in contour, and arranged radially in concentric series about a common center diminishing in size toward 50 said center point, and radially extending depending flanges on the end face of the said plate member, said flanges and openings being arranged in alternate relation on the plate, whereby said flanges may direct 55 heat to the openings.

In testimony whereof I affix my signature in presence of two witnesses.

GERTRUDE CRUMLEY.
